UNITED STATES PATENT OFFICE.

CHARLES EUGEN LANCELOT BROWN, OF ROEMERBURG, BADEN, SWITZERLAND.

AUTOMATIC ALTERNATING-CURRENT CONTACT APPARATUS.

No. 918,417.

Specification of Letters Patent.

Patented April 13, 1909.

Original application filed November 7, 1903, Serial No. 180,201. Divided and this application filed August 27, 1906. Serial No. 332,178.

To all whom it may concern:

Be it known that I, CHARLES EUGEN LANCELOT BROWN, a subject of the King of Great Britain, residing at and whose post-office address is Roemerburg, Baden, Switzerland, have invented certain new and useful Improvements in Automatic Alternating-Current Contact Apparatus; and I do hereby declare the following to be a full, 10 clear, and exact description of the invention, such as will enable others skilled in the art to which it appertains to make and use the same, reference being had to the accompanying drawings, and to letters or figures of reference marked thereon, which form a part of this specification.

The present invention relates to an automatically operating alternating current contact apparatus designed to operate an electro magnetic circuit breaker in the main circuit, being a division of my application Serial No. 180,201, filed November 7, 1903.

This device comprises an induction device which by reason of the return current is actuated to close a local circuit containing the electro-magnetically operated switch.

In the accompanying drawings in which like parts are similarly designated, Figure 1, is a side elevation. Fig. 2, is a front view 30 and Fig. 3, is a diagram illustrating the operation of the device.

The apparatus comprises a disk of conductive but non-magnetic material fixed on a shaft 2 that is rotatively mounted in a frame 3, and rotating between a plurality of laminated horse-shoe magnet cores 4 whose poles as shown in Fig. 2, are but a slight distance from the faces of the disk. On the laminated iron cores 4 of which two are shown, are the 40 energizing coils 5 inserted directly or indirectly through the medium of transformers in the electric circuit to be controlled. A permanent magnet 6 has its poles close to the disk and is for the purpose of dampening the 45 movements of the disk and preventing its oscillation.

On the axis 2 of the disk 1 is secured a drum 7 on which is, when the disk rotates, wound a string 9 or the like carrying at its 50 end a weight or weights 8. Near the disk 1 is a contact spring 10 whose forward curved end lies in the path of a pin 11 secured to the disk 1. Through the coil 5 of one of the magnets 4 passes the main current or it may 55 be a current dependent on and transformed

from the main current and is dependent upon the amperage while the coil of the other magnet lies in a circuit in parallel across the main circuit and is dependent on the voltage in the line.

In Fig. 3, I have shown a diagram indicating the use of the instrument in connection with a three-phase line, in which 12 and 12^a are suitable transformers, the primary of the former inserted in one of the three-phase line 60 wires and the primary of the latter connected across the other two line wires. An ammeter 13 (A) is inserted in the secondary circuit of the first named transformer with one of the coils 5. A volt-meter V is connected 70 across the secondary circuit of the other transformer 12^a and in said circuit is the coil of the other electro-magnet.

Both magnets 4, 5 in conjunction exert a turning moment on the disk 1 in the same direction the value of which turning moment is dependent upon the strength of the working current in the line, but the direction in which the turning moment is exerted alters as soon as the working current is changed to a reverse current. The weight 8 carried by the cord 9 on drum 7 acts in opposition to the normal turning moment exerted on the disk and the latter will be set in rotation as soon as the opposing turning moment exerted by the weight is overcome by that exerted on the disk by the magnets and the cord with the weight will be wound up on the drum until the pin 11 strikes the frame and prevents any further rotation of the disk and winding up of the cord as shown in Figs. 1 and 2. When a reverse current is set up in the line and when the turning moment exerted by the weight overcomes that exercised by the electro-magnets, the disk will rotate in an 95 opposite direction until pin 11 strikes the contact spring 10 whereupon the independent circuit 14, 15, 16, is closed to energize the electro-magnet 16 in said circuit to actuate the circuit breaker 17 in the main circuit. 100

I claim,

1. The combination with an electro-magnet adapted to be included in one conductor of a three phase electric circuit, a second electro-magnet adapted to be included between the other two conductors of the circuit, and a disk mounted to rotate between the poles of the magnets; of terminal contacts, and means operated by the disk to close said contacts when reverse current is passing in 110

the main line, means to fix the minimum current at which the disk will rotate and means to regulate the time in which the terminals are closed for the current selected.

2. The combination with two electro-magnets, one of which is adapted to be included in one of the conductors of a three phase electric circuit and the other between the remaining two conductors of said circuit and a disk mounted to rotate between the magnets; of terminal contacts a flexible suspension adapted to be wound up by said disk, the length of which suspension determines the

time when the contacts will be closed after the actuating current begins to drive the disk, and a weight or weights attached to said suspension that determine the current necessary to rotate the disk.

In testimony that I claim the foregoing as my invention, I have signed my name in presence of two subscribing witnesses.

CHARLES EUGEN LANCELOT BROWN.
